UNITED STATES PATENT OFFICE.

GEORGE SIFFERT, OF BROOKLYN, NEW YORK.

EMBOSSING OR PRINTING DIE OR PLATE AND METHOD OF FORMING THE SAME.

1,370,057.

Specification of Letters Patent.

Patented Mar. 1, 1921.

Application filed May 25, 1920. Serial No. 384,133.

To all whom it may concern:

Be it known that I, GEORGE SIFFERT, a citizen of the United States, and resident of the borough of Brooklyn, county of Kings, 5 city and State of New York, have invented certain new and useful Improvements in Embossing or Printing Dies or Plates and Methods of Forming the Same, of which the following is a description.

10 The present invention relates to improvements in embossing or printing dies or plates, and methods of forming the same, and particularly a reproduced die or plate formed in duplication of an original or master die. Heretofore such plates have been produced for the most part as electrotypes, and an object of the present invention is to enable the production of duplicates in a relatively less expensive manner, and with 20 a great saving in labor, time, and necessary equipment and apparatus.

Other objects are to provide a die which will be sharp in its outline, accurate, and will be thoroughly efficient in use.

25 With these and other objects in view, an embodiment of my invention is disclosed in the accompanying drawings, and this embodiment will be hereinafter more fully described with reference thereto, and the invention will be finally pointed out in the 30 claims.

In the accompanying drawings:

Figure 1 is a vertical sectional view showing the first step in the formation of the die, 35 namely, the pressing of a thin metal plate between the original or master die, and the matrix.

Fig. 2 is a similar view showing the plate pressed between the original die and the 40 matrix.

Fig. 3 is a plan view of the inner side of the pressed plate.

Fig. 4 is a sectional view taken on the line 4—4 of Fig. 3.

45 Fig. 5 is a sectional view through the plate and mold showing the parts in position to receive the molten metal forming the backing.

Fig. 6 is a plan view of the face side of a 50 finished plate, and,

Fig. 7 is a sectional view taken along the line 7—7 of Fig. 6.

Similar reference characters indicate corresponding parts throughout the several figures of the drawings.

Referring particularly to Figs. 1 and 2,

the die, according to the present embodiment of my invention, comprises a thin metal plate 10 of brass, copper, tin or other suitable metal, provided with an upturned 60 rim 11, substantially at right angles thereto, and having the design impressed therein in either relief or intaglio, the impression being produced directly from the original or master die or chase of type, the latter in 65 producing printing plate reproductions.

Soldering acid 13 is applied to the inner side of the plate to produce a suitable surface to cause adherence of the backing, and a sheet of tin-foil 14 is placed upon the plate 70 for the purpose of causing the same to remain flat during the application of the backing. The backing 15, which may be of any suitable metal, such as spelter, lead, pewter or the like, is applied in molten state, being 75 confined within the rim 11 of the plate, and is combined substantially homogeneously with the tin-foil and upper surface of the plate, the soldering acid causing an intimate adherence with the plate. The sides 80 and back of the finished block may be planed, filed or otherwise suitably finished.

The method of forming the dies or plates consists in first placing the original die 16 in the upper part 17 of a press, and producing a matrix 18 in the well-known manner, from papier mâché, plaster Paris, or other suitable material adapted to be rendered hard by suitable well-known methods, a side wall or framing portion 19 being 90 formed about the matrix, conforming to the periphery of the die 16, and forming a pocket into which the die is adapted to be moved in slightly spaced relation thereto.

The thin metal plate 10 is placed upon 95 the matrix, as indicated in Fig. 1, the same being of such dimension as to extend substantially beyond the periphery of the die 16, and thereupon the press is operated to move the die into the pocket, thereby 100 impressing the design into the thin metal plate, and forming the upturned rim 11 between the side wall 19 and the periphery of the die 16, as shown in Fig. 2. The plate is now ready to be provided with a solid backing, and as a preliminary to this, the inner side plate is covered with a suitable binding medium, as for instance, soldering acid 13, and above the same there is placed a thin sheet of tin-foil 14. The plate is then 110 placed upon a flat base 28, and the rim 11 is preferably confined within a frame 21,

and the molten metal for forming the backing 15 is poured upon the plate, being confined within the rim 11, and combining intimately with the inner side of the plate by means of the soldering acid and the tin-foil. The tin-foil has for its purpose, the prevention of warping of the plate, so that it remains flat. The rim 11 also serves to maintain the plate rigid against warping, so that a flat surface is maintained. The surface of the backing is then suitably finished to produce a smooth rear surface and the desired thickness to the block. The reproduced die is now ready for use. It is obvious that the die will equal, if not surpass, the electrotype reproductions heretofore in use, in all of their necessary characteristics. As a result of the direct impressing of the face plate of the die from the original or master die, a very much sharper and exact reproduction is produced than has been the case with electrolytic methods. The dies may be produced quickly, economically, and with the use of very little apparatus.

I have illustrated and described a preferred and satisfactory embodiment of my invention, but it is obvious that changes may be made therein within the spirit and scope thereof, as defined in the appended claims.

I claim:

1. A duplicate die for printing, embossing or stamping, comprising a thin metal plate having impressed therein a configuration in strict conformity with an original die, and adapted to be used in place thereof, and reinforcing means extending wholly around the marginal edge of the plate adapted to prevent warping and bending of the plate during manufacture and use.

2. A duplicate die for printing, embossing or stamping, comprising a thin metal plate having impressed therein a configuration in strict conformity with an original die, and provided with a marginal flange extending

entirely around the plate for reinforcing the plate and preventing warping and distortion of the same.

3. A duplicate die for printing, embossing or stamping, comprising a thin sheet metal die having a configuration in strict conformity to the original die or plate, and corresponding to the matter desired to be printed, embossed or stamped, and adapted to be used in place of the original die, said die having a marginal flange extending entirely around the die and adapted to be incorporated with a backing.

4. A duplicate die for printing, embossing or stamping, comprising a thin sheet metal die having a configuration in strict conformity to the original die, and corresponding to the matter desired to be printed, embossed or stamped, and adapted to be used in place of the original die, said die having marginal flanges extending wholly around the die and bent rearwardly therefrom, and a backing incorporated with said die and flanges.

5. The herein described method of forming duplicate dies or plates, which consists in subjecting a thin metal plate to the action of a die and matrix whereby to cause the thin metal plate to acquire an impression and to provide marginal flanges at the edge of the thin plate extending rearwardly, coating the rear surface of the thin metal plate so impressed with a soldering acid, covering the soldering acid with a second thin strengthening plate, placing the two plates thus combined in a mold, and pouring molten backing metal into the cavity provided by the flanges of the first mentioned thin metal plate whereby such backing material may be incorporated therewith.

In testimony that I claim the foregoing as my invention, I have signed my name hereunder.

GEORGE SIFFERT.
